(57) **CLAIM**

The ornamental design for a process cartridge for image forming apparatus, as shown and described.

DESCRIPTION

FIG. 1 is a front elevation of a process cartridge for image forming apparatus according to the present invention.

FIG. 2 is a rear elevation thereof;

FIG. 3 is a top plan view thereof;

FIG. 4 is a bottom plan view thereof;

FIG. 5 is a right side elevation thereof; and,

FIG. 6 is a left side elevation thereof.

The broken lines depict environmental subject matter only and form no part of the claimed design.
